CLAIM

The ornamental design for a pant diaper, as shown and described.

DESCRIPTION

FIG. 1 is a front view of a pant diaper showing our new design;

FIG. 2 is a rear view thereof;

FIG. 3 is a right side elevational view thereof;

FIG. 4 is a left side elevational view thereof; and,

FIG. 5 is a perspective view thereof.

The broken lines in the figures are included for the purpose of illustrating environmental structure and form no part of the claimed design.

1 Claim, 5 Drawing Sheets
